THERMOSTATIC CONTROL FOR HEATERS

Filed Nov. 25, 1927

UNITED STATES PATENT OFFICE

HOWARD I. PIATT, OF LANSING, MICHIGAN, ASSIGNOR TO MOTOR WHEEL CORPORATION, OF LANSING, MICHIGAN, A CORPORATION OF MICHIGAN

THERMOSTATIC CONTROL FOR HEATERS

Application filed November 25, 1927. Serial No. 235,639.

The present invention has for its object the thermostatic control of fuel burners and particularly as applied to water heaters, although it is equally applicable to house heating systems.

Obviously variations in detail from the structure herein shown and illustrated by way of exemplification will readily suggest themselves to one skilled in the art without departing from the spirit of the invention as set forth in the appended claims.

In the drawing, showing an improved embodiment,

Fig. 1 is a section through a water heater equipped with the invention;

Fig. 2 is an enlarged sectional detail of a thermostat; and

Fig. 3 is a cross section through the needle valve near its operative point.

20 A water heater, the details of which form no part of the present invention, is indicated at 11 with a main body of water 12 heated by means of the burner 13 fed with fuel from the tank 14 by way of the fuel line 15. Interposed in the fuel line is a head-determining float chamber 16 and level-determining float chambers 17 and 18, the details of which head and level controls form the subject matter of a co-pending application, Case No. 7092.

30 Also disposed in the feed line is a thermostat 19 in the form of a tubular body having at one end an enlarged valve-containing chamber 20 with an inlet port 21 and an outlet port 22 for the fuel.

35 A shell 23 is seated, preferably removably, in that end of the tubular body 19 opposite the valve chamber 20 and has its extreme end closed by the screw plug 24. Within this shell, forming a part of the tubular body, is 40 mounted a bimetallic thermostatic bar 25, the component parts of which are unequally affected by variations in temperature. An extension arm 26 extends from the bimetallic bar through the tubular body to a point of 45 articular connection with the needle valve stem 27, the end 28 of the arm engaging within a cage 29 carried by the valve stem, whereby as the arm moves under the impulse of the bimetallic members 25 the valve stem will be 50 seated and lifted from its seat. The adjust-

ment of the valve is provided for by a kerf 30 in the upper threaded end of a spindle 27a, access being had thereto by means of a screw plug 31. The operative lower end 32 of the needle valve stem has a limited area of its seating face formed eccentric to the seat, preferably by flattening as indicated at 33.

That end of the tubular body 19 opposite the valve chamber 20 is shown as screw threaded at 34 for insertion in a boss 35 of the inner wall 36 of the heater, whereby the extreme end of the tubular body formed by the shell 23 is projected within the heated area here represented as the body of water 12.

It will be readily understood that the rise in temperature of the water 12 will act upon the thermostatic bar 25 and its extension arm 26 to release the needle valve and permit it to drop to its seat; whereas a lowering of the temperature will, through the same means, cause a lifting of the needle valve from its seat, thus controlling the flow of fuel to the burner to an extent calculated to maintain the water at approximately a desired temperature.

Inasmuch as it will be desired to maintain a constant pilot flame at the burner, a reduced supply of fuel to the burner must be provided for even when the needle valve is closed. This is accomplished by the provision of the flat area on the needle valve which permits of a bleeding of the valve and the passage of sufficient fuel to maintain the pilot flame.

I claim:

1. In a thermostatic control, the combination with a water heater, a burner, and a liquid fuel line, of a tubular body having at one end an enlarged chamber with an inlet and an outlet port for the fuel, a needle valve seated within the enlarged chamber in the outlet port, a relatively short bimetallic thermostatic bar mounted in the other end of the tubular body, that end of the body containing the thermostatic bar being threaded for insertion through a heater wall into the heated water, and an articulated extension arm from the bar into articular connection with the needle valve stem, whereby to control the flow of fuel to the heater by varia-

tions in the water temperature, the needle valve provided with a flattened area on its seating face whereby to provide a constant reduced supply of fuel to a pilot flame when 5 the valve is seated.

2. In a thermostatic control, the combination with a heater, a burner, and a liquid fuel line, of a tubular body having at one end a separate tubular member therewithin and 10 at the other end an enlarged chamber with an inlet and an outlet port for the fuel, a needle valve seated in one of the ports, said needle valve having a portion flattened eccentric to the seat to afford a by-pass, a relatively short 15 bimetallic thermostatic bar mounted in the separate tubular member and subject to contact with the liquid fuel and to the influence of the fluid within the heater, that end of the tubular body containing the separate tubular 20 member and thermostatic bar being threaded for engagement with the wall of a heater, and an articulated connection disposed between the needle valve stem and the end of the thermostatic bar, said connection extending 25 through the tubular member, whereby to control the flow of fuel to the burner in response to the temperature within the heater.

3. In a thermostatic control, the combination with a water heater, a burner, and a liquid fuel line, a hollow body having its interior in communication with the liquid fuel line, a needle valve disposed within the hollow body and controlling the outlet port 30 therefrom, a thermostat within the hollow body, an articulated connection between the thermostat and the needle valve, the thermostat being mounted in a separate hollow member disposed within the water of the 35 heater and subject to the temperature thereof to open and close the valve in response to temperature fluctuations within the water heater, whereby to control the flow of fuel to the burner, the needle valve being provided with an eccentric area on its seating 40 face to provide a constant reduced supply of fuel to a pilot flame when the needle valve is seated.

In testimony whereof I have hereunto subscribed my name.

HOWARD I. PIATT.
